CLAIM

We claim the ornamental design for flashlight, as shown and described.

DESCRIPTION

FIG. 1 is front/top/right-side isometric view of a first embodiment of a flashlight showing my new design;

FIG. 2 is a rear elevational view thereof;

FIG. 3 is a right-side elevational view thereof; the left-side elevational view being a mirror image and, therefore, not shown;

FIG. 4 is a front elevational view thereof;

FIG. 5 is a bottom plan view thereof; and,

FIG. 6 is a top plan view of another embodiment thereof.
